Patented Mar. 1, 1921.

UNITED STATES PATENT OFFICE.

LEO G. HAASE, OF PASADENA, CALIFORNIA.

ADJUSTABLE SHUT-OFF BOX FOR GAS AND WATER.

1,370,207.

Specification of Letters Patent.

Patented Mar. 1, 1921.

Application filed August 9, 1919. Serial No. 316,446.

To all whom it may concern:

Be it known that I, LEO G. HAASE, a citizen of the United States, residing at Pasadena, in the county of Los Angeles and State of California, have invented new and useful Improvements in Adjustable Shut-Off Boxes for Gas and Water, of which the following is a specification.

My object is to make an adjustable shut-off box for gas and water meters, and my invention consists of the novel features herein shown, described and claimed.

Figure 1 is a perspective of an adjustable shut-off box for gas and water meters embodying the principles of my invention.

Fig. 2 is a sectional elevation showing the adjustable shut-off box in position for use, the view being taken on the line 2—2 of Fig. 3 and looking in the direction indicated by the arrows.

Fig. 3 is a horizontal sectional detail on the line 3—3 of Fig. 2 and looking upwardly as indicated by the arrows.

The gas or water pipe 1 is usually laid some distance below the surface 2 of the sidewalk and has a shut-off valve 3. The distance from the pipe 1 to the surface 2 varies and I provide an adjustable shut-off box comprising the lower section 4 and the upper section 5 telescoping upon the lower section 4, so as to readily make the upper end face 6 of the box level with the surface 2 of the sidewalk.

The lower section 4 is rectangular in plan and has notches 7 extending from its lower edges to receive the pipe 1 and has a vertical chamber 8 large enough to provide a ready access to the valve 3. The sections 4 and 5 are preferably made of cement or concrete.

A series of notches 9 is formed in two diagonally opposite corners of the lower section 4, said corners having beveled outer faces 10 at angles of 45° to the main side faces, and said notches 9 being in horizontal planes.

A U-shaped yoke 11 is formed of iron and

is bent to produce a central portion 12 fitting the smooth corner 9 and end portions 13 and 14 fitting the diagonally opposite notched corners 9. The yoke 11 may be moved up and down from one level to another.

The upper section 5 is formed of concrete and is large enough to readily telescope outside of the section 4 and has diagonal inner faces 15 at its corners to fit the faces 10. The outer section 5 rests upon the yoke 11 and by moving the yoke 11 up or down the aggregate height of the face 6 may be made to suit. A seat flange 16 is formed at the top of the section 5 and the cover 17 fits upon the flange 16, there being an opening 18 through the cover.

In the practical operation when the distance from the ground surface 19 to the surface of the sidewalk has been determined, the yoke 11 is placed in the proper notches, the portion 5 slid down upon the portion 4 against the yoke 11 and the box set upon the surface 19, earth tamped around the box and the cover 17 applied and the job is complete.

Preferably, the yoke 11 fits in a recess 20 extending into the lower end of the section 5, so that the flange 21 will cover the yoke and reduce the liability of the yoke expanding to let the upper section 5 down.

Various changes may be made without departing from the spirit of my invention as claimed.

An adjustable shut-off box for gas and water conduits comprising a lower section rectangular in form composed of concrete having notches on diagonal corners, a yoke adapted to fit the notches, and an upper section formed of concrete to fit over the lower section slidably and rest upon the yoke, the upper section being provided with a suitable cover.

In testimony whereof I have signed my name to this specification.

LEO G. HAASE.
